Assistant Examiner — Jennifer Watkins

(57) **CLAIM**

The ornamental design for footwear, as shown and described.

DESCRIPTION

Fig. 1.1 is a top, front, left perspective view of the footwear showing our new design;

Fig. 1.2 is a top plan view thereof;

Fig. 1.3 is a bottom plan view thereof;

Fig. 1.4 is a left side elevation view thereof;

Fig. 1.5 is a right side elevation view thereof;

Fig. 1.6 is a front perspective view thereof; and

Fig. 1.7 is a rear perspective view thereof.

The lines of uneven length represent stitching and form part of the claimed design.
